(57) **CLAIM**

The ornamental design for a notebook computer, as shown and described.

DESCRIPTION

FIG. 1 is a front perspective view of a notebook computer, showing our new design;

FIG. 2 is a front view thereof;

FIG. 3 is a rear view thereof;

FIG. 4 is a left-side view thereof;

FIG. 5 is a right-side view thereof;

FIG. 6 is a top plan view thereof;

FIG. 7 is a bottom plan view thereof;

FIG. 8 is a top-front perspective view of the notebook computer of FIG. 1, in which a display part of the notebook computer rotates on a hinge in a first position shown by FIG. 8;

FIG. 9 is a rear perspective view of the notebook computer of FIG. 1, in which a display part of the notebook computer rotates on a hinge in a second position shown by FIG. 9; and, FIG. 10 is a top-rear perspective view of the notebook computer of FIG. 1, in which a display part of the notebook computer rotates on a hinge in a third position shown by FIG. 10.

The broken lines are for environmental purposes only and form no part of the claimed design. The shade lines in the figures show contour and not surface ornamentation.
